TACHOMETER ARRANGEMENT FOR
OUTBOARD MOTORS

Elmer C. Kiekhaefer, Cedarburg, Wis.

Application September 5, 1947, Serial No. 772,345

3 Claims. (Cl. 74—12)

1

This invention relates to outboard motors and has particular reference to a speed recording device for an outboard motor.

The primary object of the invention is to provide means for rendering the drive shaft of a tachometer accessible to the engine shaft of the outboard motor.

A specific object is to provide an outboard motor having a starter shaft hollowed to accommodate a driving connection between the tachometer and engine shaft.

Another object of my invention is to provide a starter shaft, hollowed to accommodate the cable and casing of a tachometer anchored remotely from the outboard motor.

Another object is to provide a starter shaft, hollowed to serve as a housing for the drive shaft of a tachometer mounted directly to the outboard motor.

Other objects and advantages will become apparent upon reading the following specification and upon examination of the drawings in which:

Fig. 1 is a side elevation of an outboard motor employing the invention in one form;

Fig. 2 is a fragmentary sectional side view of the outboard motor employing one form of the invention;

Fig. 3 is a fragmentary sectional front view of the outboard motor employing a modified form of the invention;

Fig. 4 is a detail plan view of the upper end of the engine shaft; and

Fig. 5 is a fragmentary sectional front view of the outboard motor employing another modified form of the invention.

The outboard motor in general comprises a power head 1, a drive shaft housing 2, a propeller shaft housing 3, a propeller 4, a boat clamping bracket 5 and a tiller 6.

The power head 1 includes an internal combustion engine 7 housed in a pair of casings 8 and 9 secured together, the parting line of said casings being embraced by a protector rim 10.

The engine 7 may have one or more pistons 11 and cylinders 12 with a single crankshaft 13 and may have a cylinder block 14 and a crank-case casting 15. The upper end of the crank-shaft 13 supports the magneto 16, the flywheel 17 and a starter ratchet wheel 18. A rope pull type starter pulley 19 with a rewind spring 20 supports the starter pulley 19 for rotation on the starter shaft 21.

A cover 23 is nested in the upper face of casing 8 and serves as a support for the engine starting mechanism. The starter shaft 21 may have an outwardly flared flange 24 and screws 25 may be used to secure the starter shaft 21

2

to cover 23. It will be noted that the starter shaft 21 is in concentric registry with engine shaft 13.

In outboard motor construction it is desirable to know the R. P. M. at which the engine shaft is revolving, particularly when selecting the propeller with the proper diameter and pitch for maximum performance. For example, an outboard motor of the type employed herein, operates at near maximum efficiency with near maximum horsepower output when the crank-shaft 13 is revolving at 4400 R. P. M. Consequently, I have provided an expedient and economical means for permanently associating a tachometer with an outboard motor so that an R. P. M. reading of the engine shaft is constantly available.

In Fig. 2, I have shown one form of my invention in which the cover 23 is provided with a bore 27 which registers with a bore 28 in starter shaft 21. A conventional tachometer 29 may be secured to some part of the boat 30 remotely from the outboard motor so that the dial 31 faces the operator of the boat. The tachometer 29 is provided with a flexible housing 32 which serves as a bearing for the flexible drive shaft 33. An externally threaded sleeve 34 may be welded or brazed to the end of the housing 32 and is threaded into the internally threaded lower portion of bore 28 in starter shaft 21. The housing 32 bottoms against an annular shoulder 35. The lower portion of the starter shaft 21 may have an enlarged bore 36 to accommodate shaft seal 37 for retaining lubricant in housing 32. The flexible drive shaft 33 has a driving tip 38 which has an internal bore at one end to receive the end of flexible shaft 33 and has a driving ear 39 near its other end. The ear 39 may be formed in the drive tip 38 by a swaging process. The end of the engine shaft 13 has a drilled hole 40 which may be countersunk at 41 to facilitate insertion of drive tip 38. A saw slot 42 is cut in the engine shaft and opens into drilled hole 40 to receive the driving ear 39. Thus it can be seen that rotation of engine shaft 13 is directly transmitted to the flexible drive shaft 33, through the medium of the driving ear 39 and the R. P. M. of the engine shaft is recorded by the tachometer 29.

The flexible shaft 33 may be assembled by inserting the tachometer end of the shaft into bore 28 through the flexible housing 32 prior to the time that the cover 23 and its attached starter assembly is inserted into place in casing 8. Then the cover 23 and its associated parts are brought into position over casing 8 and manipulated until the driving ear 39 slips into the saw

slot 42 in the engine shaft. Then the cover 23 is secured to casing 8 by suitable screws. Thus it is apparent that the starter shaft 21 serves the dual function of supporting the starter pulley 19 and its associated parts externally thereof, while accommodating the tachometer drive shaft 33 and housing 32 internally thereof.

In the form of my invention as disclosed in Fig. 3 the starter shaft 21a may have an annular flange 24a which is nested in a circular recess 44 in cover 23a and secured to the cover with screws 25a. The starter shaft has an internal bore 28a of sufficient diameter to provide a clearance between the cylindrical wall of the bore and the driving tip 45. The driving tip 45 may have a squared nose portion 46 which is received in a correspondingly shaped hole 47 in the upper end of the engine shaft 13a thereby establishing a driving connection between engine shaft 13a and driving tip 45. The square shaped hole 47 may be obtained by running a broaching tool into a drilled hole 48. The drilled hole 48 is countersunk at 49 to facilitate entry of driving tip 45 into hole 47.

The upper end of starter shaft 21a has an externally threaded nipple 50 protruding beyond the face of cover 23a, the interior of said nipple being machined to provide a semi-spherical receptacle for the spherically shaped upper end 51 of driving tip 45. An externally threaded nut 52 having a semi-spherical interior mating with the semi-spherical interior of the nipple 50 to form a socket for the spherical upper end 51 of drive tip 45. The flexible housing 32a has a female end fitting 53 threaded onto the nut 52 and nipple 50. The flexible shaft 33a has a driving tip 54 with an integral driving ear 55 received in a saw slot 56 which opens into the drilled hole 57. Thus the engine shaft 13a drives the connector 45 which in turn drives the flexible shaft 33a thereby affording a reading at the tachometer 29a of the R. P. M. of the engine shaft. It will be noted that the bore 28a in the starter shaft 21a serves as a housing for the connector shaft 45 and the clearance between the shaft and the wall of bore 28a in combination with the ball and socket joint at the upper end of shaft connector 45 permits some misalignment between the connector shaft 45 and the bore 47 of the engine shaft 13a which may be present when cover 23a is assembled into casing 8a.

In the form of the invention as disclosed in Fig. 5, I have mounted the tachometer 29b directly onto the cover 23b by means of a supporting bracket 59 and bolts 60. Rubber pads 61 interposed between the bracket legs and the cover 23b serve to damp out vibration so that a more accurate reading may be obtained from the tachometer 29b. The engine shaft 13b has a drilled hole 40b with a saw slot 42b for receiving the driving ear 39b of connector shaft 63 thereby establishing a driving connection between engine shaft 13b and connector shaft 63. The starter shaft has a bore 28b mating with a bore 27b in cover 23b and the starter shaft 21b and cover serve as a housing and bearing for the connector shaft 63. A pair of seals 64 and 65 retain lubricant within the bores 27b and 28b. The connector shaft 63 may be threaded into the driven shaft 66 of the tachometer 29b. The tachometer has an externally threaded stud 67 which projects through an opening in bracket 59 and a pair of nuts 68 and 69 secure the tachometer to the bracket 59. The connector shaft 63 is assembled by being inserted through the starter

shaft 21b from its underneath side. Then the cover 23b and its associated parts are assembled into casing 8b and secured thereto. The driven shaft 66 of the tachometer is then threaded onto the upper end of the connector shaft 63 and the tachometer is secured to bracket 59 with nuts 68 and 69.

It is apparent that I have provided a comparatively simple yet economical and expedient way of providing an outboard motor with a tachometer driven by the engine shaft so as to obtain the R. P. M. reading of the engine shaft for various purposes.

Having thus described my invention what I claim is:

1. In an outboard motor, a power unit including a crankshaft, a starter device for said power unit including a pulley rotatably engageable with said crankshaft, a removable starter cover plate having a hub rotatably carrying said pulley in axial alignment with said crankshaft and axially spaced therefrom, said plate having an opening extending through said hub in axial alignment with said crankshaft, a speed indicating instrument having a shaft extending through said opening and said starter cover hub and drivably engageable with said crankshaft, and a bearing secured to and carried by said cover plate journalily supporting said instrument shaft in said opening.

2. In an outboard motor, a power unit having a crankshaft, a starter device for said power unit including a pulley rotatably engageable with said crankshaft, a starter cover plate having a hollow hub rotatably carrying said pulley in axial alignment with said crankshaft and spaced therefrom, a speed indicating instrument including a flexible shaft extending through said starter cover plate hub and drivably connected to said crankshaft, and a flexible housing for said flexible shaft secured and carried within said hollow hub and journalily supporting said flexible shaft therein.

3. In an outboard motor, a power unit having a crankshaft, a starter device for said power unit including a pulley rotatably engageable with said crankshaft, a starter cover plate having a hollow hub rotatably carrying said pulley in axial alignment with said crankshaft and spaced therefrom, a speed indicating instrument including a flexible shaft extending through said hub and drivably connectable with said crankshaft, and a flexible housing for said flexible shaft secured to and carried by said hub and journalily supporting said flexible shaft therein.

ELMER C. KIEKHAEFER.
